UNITED STATES PATENT OFFICE.

JOHN T. JANETTE, OF CHICAGO, ILLINOIS.

DESIGN FOR AN AIR-PUMP SUPPORT AND CASING.

46,095.

Specification for Design.

Patented July 14, 1914.

Application filed April 23, 1914. Serial No. 833,994. Term of patent 7 years.

To all whom it may concern:

Be it known that I, JOHN T. JANETTE, a citizen of the United States, residing at Chicago, in the county of Cook and State of Illinois, have invented a new, original, and ornamental Design for Air-Pump Supports and Casings, of which the following is a specification, reference being had to the accompanying drawing, forming a part thereof.

The figure shown in this drawing is a perspective view of a support and casing for air pumps of the type commonly used as

beer pumps, showing my new design. The upper portion of this device is made of glass, which exposes the upper part of the base portion, the latter being formed of opaque material.

I claim:

The ornamental design for an air pump support and casing as shown.

JOHN T. JANETTE.
